ERNEST AICHELE, OF IRVINGTON, NEW JERSEY.

ELECTRICAL CIRCUIT BREAKER OR INTERRUPTER.

Application filed April 16, 1925. Serial No. 23,713.

This invention relates, generally, to improvements in repeating electrical circuit interrupters; and the present invention has reference, more particularly, to a novel construction of circuit-interrupter, made in either plug or cartridge-form, respectively, adapted for connection in the ordinary sockets or clips, to provide, primarily, a safe-guard against injurious effects caused by abnormal overloads and short circuits, and, furthermore, to provide the circuit-interrupter with means, whereby the deleterious effects of a powerful current of electricity through the device will be removed from the thermostatic control-element, so that with the various circuit-interrupters of the different watt-powers, uniform control-element can be used, without destroying their usefulness when an exceptionally strong or powerful shock or overload occurs in the circuit.

The present invention, therefore, has for its principal object to provide a novel, reliable, and simply constructed, as well as an automatically operating circuit-breaker or interrupter, which is especially adapted for use with the usual screw-threaded receiving sockets of a switch-board, or a meter-board, or the like; or, in slightly modified cartridge-form with the usual receiving clips, for interrupting an electric circuit in case of an overload or a short circuit, the general construction of the contact-elements of the device being such that the device can be used over and over, without deteriorating effect to either the device or to the installation in which the device is located.

In addition to the above-mentioned objects, however, the invention has for its further object to provide in connection with the automatically operating interrupter-mechanism of the device, means which will divide the path of the excessive over-load circuit produced, so that a reduced or normal current will flow through the thermostatic control-member, thereby permitting in all instances such members to be made uniform, and to permit such members to be constructed of a thin deflecting metal, without danger of melting or otherwise rendering inoperative the usefulness of the thermostatic control-member for the purposes for which it is intended.

Other objects of the present invention not at this time more particularly enu-

merated will be clearly understood from the following detailed description of the said invention.

With the various objects of the present invention in view, the said invention consists, primarily, in the novel electrical circuit-breaker or interrupter hereinafter set forth; and, the said invention consists, furthermore, in the novel arrangements and combinations of the various devices and parts, as well as in the details of the construction of the said parts, all of which will be more fully described in the following specification, and then finally embodied in the clauses of the claim, which is appended to and which forms an essential part of the said specification.

The invention is illustrated in the accompanying drawings, in which:

Figure 1 is a top-end view of a circuit-interrupter of the plug-type made according to and embodying principles of the present invention; Figure 2 is a transverse vertical section of the same, said section being taken on line 2—2 in said Figure 1, looking in the direction of the arrow *x*; and Figure 3 is a transverse vertical section of the device, said section being taken on line 3—3 in said Figure 2, looking in the direction of the arrow *y*, both of said views showing the contact-making elements of the interrupter-mechanism in their initial positions, when a complete electrical circuit is being established through the device.

Figures 4 and 5 are vertical sectional representations of the device, similar to Figures 2 and 3, respectively, showing the several contact-making elements of the interrupter-mechanism in their automatically separated relation, caused by an overload or short circuit in the main line; and Figure 6 is a horizontal sectional representation of the device, said section being taken on line 6—6 in said Figure 3.

Figures 7 and 8 are diagrammatical sectional representations of certain parts of the device, respectively, in their initial circuit-completing relations and in their separated relation, said views illustrating more particularly the path of the electric circuit through said parts, in Figure 7 when there is a normal circuit through the device, and in Figure 8 when an extreme circuit is produced through the device, due to an over-load or a short circuit.

Figure 9 is a side elevation, and Figure

10 an end elevation of a circuit-interrupter embodying the principles of the present invention, but made in the general cartridge-form; Figure 11 is a longitudinal vertical sectional representation of the same, showing the several contact-making elements of the interrupter-mechanism in their initial positions, when a complete electrical circuit is being established through the device; 10 Figure 12 is a vertical cross-section of the device, said section being taken on line 12-12 in said Figure 9; and Figure 13 is a horizontal section of the same, said section being taken on line 13-13 in said Figure 11.

Figure 14 is a bottom view of the circuit-interrupter; Figure 15 is a vertical section of the same, said section being taken on line 15-15 in said Figure 13, showing certain 20 portions of the device normally in their non-interrupted contact-making relation; and Figure 16 is a similar sectional representation of the same parts, but in their relative positions, when the electric current 25 has been interrupted.

Similar characters are employed in all of the said herein-above described views, to indicate corresponding parts.

Referring now more particularly to Figures 1 to 8 of the drawings, the reference-character 1 indicates a main body in which the interrupter-mechanism is arranged, the body in this case being of the plug-form or type and being made of a suitable insulating material, such as bakelite, porcelain, or other suitable insulating material. Upon its lower portion, the said body is made with a reduced part 2, which is externally convoluted or screw-threaded, as at 3, for the 30 reception and arrangement thereon of a correspondingly convoluted or screw-threaded collar or ring 4 made of suitable metal, as brass, for screwing into the usual internally screw-threaded receiving socket of a meter or switch-board, or the like. The 35 lower portion of said reduced part 2 is also socketed, as at 5, for suitable arrangement therein of a metal thimble or nut 6, which is internally screw-threaded, as at 7, for 40 reception of a contact-screw 8, and upon which screw is also placed a metal plate or disc 9. In its upper part, the said body 1 is 45 suitably chambered, as at 10, and in communication with said chamber, and extending 50 downwardly in said body is a socketed part 11. Suitably mounted upon the upper end-surface of said body 1 is a suitably 55 formed cover or closure 12, also made of a suitable insulating material, said cover being 60 secured in closing position upon said body by an arrangement of screws 13, or other suitable fastening means. The said cover or closure 12 is also made with an 65 opening 14, in alinement with the previous- ly-mentioned socketed part 11. Leading

from the chamber 10 of the body 1, and extending downwardly through the reduced part 2 of said body, is a suitably shaped duct 15. The interrupter-mechanism arranged within the said body 1, in the manner to be presently described, and which as will be evident is an automatically operating mechanical switch, consists, essentially, of a suitably shaped manipulating stem or plug, as 16, arranged within the chamber 10, 75 which has its upper end-portion 17 extending into the opening 14, and extends normally slightly above the outer face of the cover or closure 12, substantially as illustrated in Figures 2 and 3 of the drawings. 80

The lower end-portion of the said stem or plug 16 is preferably socketed, as at 18, and is supported upon a coiled spring 19, one end of which extends into said socket 18 and the other end of which rests in the previously 85 mentioned socket 11, as indicated in Figures 2 and 3 of the drawings. Upon its one side, the said stem or plug 16 is provided with a suitably formed projection 20, providing a stop-member, said projection extending laterally into the chamber 10, at a point directly above and substantially in alinement with the previously mentioned duct 15. Suitably secured by means of solder, or otherwise, to said metal plate or disc 9 is 90 an angular end-portion 22 of a resilient or spring-arm 21, made of a thermostatic metal, which extends in an upward direction into and through the duct 15, with the upper end-portion 23 thereof projecting into the chamber 10. This end-portion is usually doubled upon itself, as shown, and is formed with a right-angled extension, as 24, which acts as a holding or retaining means, when brought into engagement with the 95 stop-member 20 of the stem or plug 16. Suitably imbedded in the said stem or plug 16, with its respective end-ports 26 and 27 projecting on opposite sides of the said stem or plug, is a metal plate or bar 100 25.

Imbedded within the body-portion 1 and the extension 2 of the plug is an electrical lead or conductor 28, having its lower end-portion 29 suitably connected with, and in 115 electrical contact with the thimble 6, and having its upper end-portion extending into the chamber 10, and terminating in a right-angled or other suitably shaped contact-producing member, as 30, with which the 120 projecting end 26 of the plate or bar 25 is normally in contact, as indicated in Figure 3 of the drawings. This lead or conductor 28, may be in the form of a flat plate or bar, or if desired may be of wire of the proper gauge which will offer little resistance to the passage of the electric current there-through. Another electrical lead or conductor 31, said lead or conductor being made of flexible metal, or the like, is also em- 125 130

ployed, said lead or conductor having its one end-portion, as 32, suitably and electrically connected with a suitable portion, preferably the doubled-over end-portion 23, of the thermostatic control-member or arm 21, as will be evident more particularly from an inspection of Figure 6 of the drawings, and having its other end-portion 33, suitably and permanently affixed to the contact member 30. Under normal conditions, the opposite end-portion 27 of the plate or bar 25 is in contact with a member 35 of another metal bar or plate 34, which extends from the chamber 10 into the body 1 and part of the reduced portion 2, in which it is embedded and has its end-portion 36 in electrical contact with a portion of the metal collar or ring 4, as represented in said Figures 3 and 5 of the drawings.

Having in the foregoing described the general construction and arrangement of the several devices and parts of the circuit-breaker or interrupter of the screw-plug form, I will now briefly set forth its use in connection with the usual receiving sockets of a meter or switch-board, and also for breaking an electric circuit when there is an overload or a short circuit.

Direction of the electric circuit through the circuit-breaker or interrupter, when screwed in the socket, and when the various members of the interrupter-mechanism have been set in the positions indicated in Figures 2 and 3, by pushing the stem or plug 16 in an inward direction, is through the screw 8, the plate or disc 9, to the end-portion 22 of the thermostatic arm 21, thence by means of the electrical lead or conductor 28 to the plate or bar 25, thence by the contact-member 35 of the plate or bar 34, and by means of its end 36 to the metal collar or ring 4, thus completing the electric circuit with the socket into which the device has been screwed. Thus, when the various parts of the device are in their set positions indicated in said Figures 2 and 3 of the drawings, a complete electric circuit is established. At the moment, however, that an overload or short circuit occurs in the main line, the increase caused by the overload, will cause the thermostatic arm 21 to move laterally within the duct 15, thereby automatically causing the disengagement or separation of the two members 24 and 20, as indicated in Figure 4. The compressed spring 19 now becomes active, causing the setting stem or plug 16 to fly in an outward direction, and thereby breaking the electric circuit, due to the separation of the end-portion 26 and 27 of the bar or plate 25 from their electrical contact with the contact-members of the respective leads or conductors 28 and 34, as will be clearly evident.

From an inspection of the diagrammatic representations of the main elements of the

device, as indicated in Figures 7 and 8 of the drawings, it will be noticed, that at the time an overload takes place, the tendency of the electrical current is to divide itself into two paths of direction, as indicated by the arrows, one path going through the lead or conductor 28, and the other through the thermostatic member 21 and the lead or conductor 31, each divided amount or quantity of current being therefore reduced in its power, so that while it deflects the member 21, it is not of such strength that the future usefulness of said member 21 will be destroyed. This action will be fully understood from an inspection more particularly of said Figure 8.

It will thus be understood that the device is readily applicable to meter or switchboards, and to any other electrical instrumentalities, in lieu of the usual and readily destructible fuse-plugs at present in ordinary use, and that the device when inserted in the line can be used over and over.

Referring now to Figures 9 to 16 of the drawings, I have shown in said figures a circuit-breaker or interrupter embodying the principles of the present invention, but in which the device is made in cartridge-form to be used with the usual spring-clips for inserting the device in a main electrical line.

In said figures, the reference character 37 indicates a block-like or rectangular main body of any suitable insulating material, which is chambered, as at 38, and is also formed with a communicating duct, as 39. Extending from the ends of said body are cylindrical, or other suitably shaped extensions 40 and 41, which are respectively encased in the tubular contact-making shells 42 and 43, the main portions of said shells being embodied in the said main body 37 by being imbedded therein, during the molding process. The lower portion of the said main body 37 is also provided with a receiving socket 44, and its upper open portion is closed by a cover 45, suitably secured to said body by means of screws 46, or other suitable fastening means. This cover 45 is provided with an opening 47. Movable disposed in said socket 44 is the lower portion of a stem or plug 48 made of insulating material, said plug resting upon a coiled spring 49, within said socket 44, substantially as represented in Figures 11 and 12 of the drawings. At its one side, the said stem or plug 48 is made with a projection 50 providing a stop, and in suitable location, the said plug is also made with a laterally extending opening 51. The upper end-portion of the said stem or plug 48 projects into and extends from the opening 47 of the cover 45, for suitable manipulation of the said plug or stem, as will be evident. Disposed within the laterally extending opening 51 of the stem or plug is a metallic con-

tact-making plate 52, said plate having its respective end-portions 53 and 54 projecting from the opposite sides of the said stem or plug 48, substantially as shown in Figure 12. Suitably connected with a portion 55 of the contact-making shell 43, by means of a screw 56, or in any other suitable manner, is a metallic conductor 57 which extends through a duct 58 and its upper portion terminating 10 in the chamber 38. Connected with said upper portion of the conductor 57 is a contact-establishing member 59, said member being angularly formed, as shown in Figure 13, and terminates directly beneath the projecting end-portion 53 of the plate 52, and with which it is normally in electrical contact. Suitably connected with a portion 60 of the contact-making shell 42, by means of a screw 61, or in any other suitable manner, 15 20 25 30 35 40 45 50 55 60 65 70 75 80 85 90 95 100 105 110 115 120 125 130 is a resilient or spring-arm 62, made of a thermostatic metal which extends in an upward direction into and through the duct 39, with the upper end-portion 63 thereof terminating in the chamber 38.

At its upper end-portion this thermostatic control-arm 62 is provided with a projection 64 which acts as a holding or retaining member when brought into engagement with the stop-member 50 of the stem or plug 48.

Also suitably mounted upon the said screw 61, so as to make electrical connection with the portion 60 of the contact-making shell 42 is a contact-making member 65, in the form of a bar, or the like, said member being imbedded in the material of which the body 37 is made, and extends in an upward direction through said material, terminating at its upper end in a contact-establishing end-portion 66. Suitably connected with the said thermostatic spring-arm 62 is a downwardly extending member 67, made of a resilient metal, from the lower end-portion of which extends at an angle, a finger or projection, as 68, formed with a contact-establishing end-member 69, extending beneath the end-portion 54 of the plate 52, and in electrical contact therewith. Under normal initial conditions, when the stem or plug 48 is depressed, the said finger or projection 68 has its lower surface-portion forcibly pressed into electrical contact-making engagement with the contact-establishing end-portion 66 of the previously mentioned member 65, as will be clearly understood from an inspection of Figure 15 of the drawings, but with which electrical contact is broken, when the spring-controlled stem or plug 48 is released and moves in an upward direction, as will be evident from Figure 16 of the drawings.

Direction of the electric circuit through this form of circuit-breaker or interrupter, when secured by means of the contact-making shells 42 and 43, between the usual spring contact-clips, and when the members of the

interrupter-mechanism have been set in the positions indicated in said Figures 11 to 15 inclusive, by pushing the stem or plug 48 in a downward direction, is through the shell 42, the screw 61, to the end-portion 66 of the member 65, thence through the finger 68 of the member 69 to the member 54 of the plate or bar 52, thence by the contact-member 53 of the plate or bar 52, and the said conductor 57, completing the electric circuit with the shell 43, and by means of the latter with the contact-clips, between which said shell 43 has been sprung. As soon, however, as an overload or short circuit occurs in the main line, the increase caused by the overload, will cause the thermostatic arm 62 to move laterally within the duct 39, thereby automatically causing the disengagement or separation of the two members 64 and 50. Immediately the compressed spring 49 becomes active, causing the stem or plug 48 to fly in an outward direction, and thereby separating the end-portions of the plate or bar 52 from contact with the several contact-establishing members, thus interrupting the circuit, as will be evident.

In all other respects, the general operation of the several elements of the circuit-interrupter is substantially the same as the operation of the elements when arranged as shown in the device which is illustrated in Figures 1 to 8 inclusive.

I am fully aware, that changes may be made in the general arrangements and combinations of the several devices and parts, as well as in the details of the construction of the said parts, without departing from the scope of the present invention as set forth in the foregoing specification, and as defined in the clauses of the claim which is appended to the said specification. Hence, I do not limit my present invention to the exact arrangements and combinations of the several devices and parts as described in the said specification, nor do I confine myself to the exact details of the construction of the said parts as illustrated in the accompanying drawings.

I claim:—

A repeating circuit interrupter, comprising a housing having external contacts, internal contacts respectively connected with said respective external contacts, a movable interrupter block within said housing having a bridging contact means imbedded transversely therein and having exposed projections to mutually engage said internal contacts, said block having an exteriorly projecting portion for manually setting the same in circuit completing position, spring means to move said interrupter block to circuit interrupting position, a detent means to normally hold said interrupter block in circuit completing position, said detent means including a flexible thermostatic arm

having one end fixed in mechanical and electrical union with one external contact, said housing having an open passage leading into the interior of said housing through which said arm extends, and a flexible shunt coupling connection between the free end of said arm and the internal contact which is

connected with the same external contact to which the fixed end of said arm is connected.

In testimony, that I claim the invention 10 set forth above I have hereunto set my hand this 9th day of April, 1925.

ERNEST AICHELE.
